DESIGN FOR A WOVEN TEXTILE FABRIC

John L. Walther, New York, N. Y.

Application June 21, 1939, Serial No. 85,593

Term of patent 3½ years

To all whom it may concern:

Be it known that I, John L. Walther, a citizen of the United States of America, residing in the city of New York, county of New York, and State of New York, have invented a new, original, and ornamental Design for a Woven Textile Fabric, of which the following is a specification, reference being had to the accompanying drawing, forming part thereof.

The figure is a plan view of a woven textile fabric, showing my new design. My design comprises a series of set, integral stripes, having the appearance of shirred ribbon, arranged on a dull woven background, as shown.

I claim:

The ornamental design for a woven textile fabric, substantially as shown and described.

JOHN L. WALThER.
